(No Model.)

H. C. BRITTAINE & P. J. SHRUM.
WIRE MAT.

No. 487,700.

Patented Dec. 6, 1892.

UNITED STATES PATENT OFFICE.

HERBERT C. BRITTAINE AND PETER J. SHRUM, OF BEAVER FALLS, PENNSYLVANIA; SAID SHRUM ASSIGNOR TO ARLINGTON D. BRITTAINE, OF SAME PLACE.

WIRE MAT.

SPECIFICATION forming part of Letters Patent No. 487,700, dated December 6, 1892.

Application filed December 14, 1891. Serial No. 415,085. (No model.)

To all whom it may concern:

Be it known that we, HERBERT C. BRITTAINE and PETER J. SHRUM, citizens of the United States, residing at Beaver Falls, in the county 5 of Beaver and State of Pennsylvania, have invented certain new and useful Improvements in Wire Mats; and we do hereby declare the following to be a full, clear, and exact description of the invention, such as will enable others 10 skilled in the art to which it pertains to make and use the same, reference being had to the accompanying drawings, which form a part of this specification.

Our invention has relation to that class of 15 mats made of wire and having wire-bound edges; and it consists in the novel construction thereof, substantially as hereinafter described, and particularly pointed out in the subjoined claim.

20 In the accompanying drawings, illustrating the invention, Figure 1 is a plan view of our improved mat. Fig. 2 is an edge view of a part of the same, and Fig. 3 is an enlarged detail view of the trimming or binding and fastener.

25 A designates the main or body part of our improved mat, B the trimming or border thereof, and C the means for fastening the trimming. The body A is composed of the pieces a a', each of which pieces consists of

30 one or more strands of wire coiled and twisted, as shown. The pieces a are laid in diagonal parallel lines, and the pieces a' are also laid diagonally and parallel with each other, but at an angle to the pieces a, which they cross 35 and with which they are intercoiled at the points of intersection. It will be observed that the angles in which the pieces a and a', respectively, extend is such as to form rhombus-shaped openings D and D' and V-shaped

40 opening D'', said openings D' being so located with respect to said openings D that their longitudinal centers will be directly opposite the ends of the same, and said openings D'' being located at the sides of the mat between

45 the junctions a'' of the pieces a and a'. The pieces a and a' are joined at the sides of the mat by twisting their ends together. The two adjacent pieces a at the respective corners of the mat are connected together by the 50 short piece a''. The binding B consists of a

continuous piece of wire bent to form the parallel strips b on each side thereof and the connecting-strips b' and b'', said strips b' joining the bottoms of two adjacent strips b and alternating with openings b², and the strips b'' joining together the tops of the strips b and extending at right angles to said strips b'. It will be observed that said binding B is located principally within the openings D'' and that it is not intercoiled with the body A. 55 It is held in place by the wire C, which is bent alternately in and out in a curvilinear course, crossing each strip b' in its passage around the mat, and also crossing itself at the points c, which latter are located opposite or within 60 the openings b² in the binding B and in the openings D' in the body A alternately. It will be observed that the pieces a and a' are bent or twisted so as to form projecting portions 1, alternating with hollows 2. This is 65 advantageous, as it increases the facility with which the mat will remove mud, &c., from the feet of the user and at the same time make it of such strength and durability as to obviate the necessity of employing supplemental 70 tie or brace rods or wires, which not only add to the expense of the mat, but tend to decrease the flexibility thereof. It will be further observed that the binding B is not directly intercoiled with the body A and also that the 75 fastener C is not intercoiled with the body of the mat except at the center of the ends thereof. This construction is advantageous in that it does not interfere with the folding of the mat 80 when desired. Thus we have provided a mat 85 of simple construction, which will possess increased effectiveness in the accomplishment of its purpose and be of increased durability without loss of flexibility.

We do not claim, broadly, a mat composed 90 entirely of wire and consisting of a body having openings, a binding, and means for holding the binding in place, since we are aware that such construction is not broadly new; but

What we do claim is—

95 The herein-described mat, consisting of the body A, binding B, and fastener C, said body consisting of the diagonal pieces a and a', crossing each other at such angles as to form V-shaped openings at the edge of the body 100

and rhombus-shaped openings within said body, said pieces *a* and *a'* being secured together at their ends and each twisted to form alternating hollows 2 and projections 1, said 5 binding B covering the edges of said body and said fastener C extending in a curvilinear course alternately in and out through the openings in the said binding, engaging the strips *b*' thereof and crossing itself within the 10 openings in said body, said fastener being intercoiled with said body only at the center of

the ends thereof, all substantially as described, and for the purpose set forth.

In testimony that we claim the foregoing we hereunto affix our signatures this 28th day of 15 September, A. D. 1891.

HERBERT C. BRITTAINE. [L. S.]
PETER J. SHRUM. [L. S.]

In presence of—

HENRY BARKER,
JOS. C. ROUZER.
